UNITED STATES PATENT OFFICE.

ERNEST E. WEMP, OF PONTIAC, MICHIGAN.

REMOVABLE SPRING-ABUTMENT.

1,215,756.

Specification of Letters Patent. Patented Feb. 13, 1917.

Application filed December 13, 1915, Serial No. 66,436. Renewed January 5, 1917. Serial No. 140,704.

To all whom it may concern:

Be it known that I, ERNEST E. WEMP, a citizen of the United States, residing at Pontiac, county of Oakland, State of Michigan, have invented a certain new and useful Improvement in Removable Spring-Abutments, and declare the following to be a full, clear, and exact description of the same, such as will enable others skilled in the art to which it pertains to make and use the same, reference being had to the accompanying drawings, which form a part of this specification.

This invention relates to removable spring abutments especially adapted for valve stems. Heretofore it has been customary to use a cupped washer with a perforation in its center through which the stem passes and in conjunction with this a second washer, 20 cotter pin or other element for holding the cupped washer in place. It is the object of this invention to do away with this additional element and so form the cupped washer that it is adapted to be held in place 25 without the use of an additional element and is both adapted to centralize itself and centralize the spring.

In the drawings,—

Figure 1 is a vertical section of a portion 30 of an internal combustion engine adjacent the valve.

Fig. 2 is an end view of the valve stem showing how the spring abutment is passed over the same in the process of putting it in 35 place.

Fig. 3 shows a similar view with the spring abutment in place.

Fig. 4 is a detail of the valve stem showing how the modified form of washer which 40 is passed laterally on to the valve stem looks when in place.

Fig. 5 shows how this washer is placed.

Fig. 6 is an end view making a similar showing.

Fig. 7 is a view of the washer provided 45 with a double cupped portion to provide a spring seat for a spring of large diameter.

a indicates the valve stem of an internal combustion engine; *b* the customary helical spring which serves to keep the valve closed. The valve stem is provided with an annular groove *c* which forms a reduced portion for the stem and which has at least one abrupt shoulder. *d* designates a cupped washer 50 which is shown in Figs. 1, 2 and 3 as provided with a compound slot, that is to say,

a central perforation adapted to fit around the reduced portion of the valve stem and a large eccentric perforation communicating with the central perforation and which 55 serves in the assembling of the washer upon the stem. The washer is passed over the stem, the stem passing through the large perforation and when the washer comes adjacent the reduced portion of the stem the 60 washer may be drawn laterally of the stem to bring it into central position with respect to the stem.

Now an important feature of this invention is to have the cupped portion of the 65 washer so that its internal diameter at the top of the dome-like cup or boss is just large enough to fit over the larger diameter of the stem so that this serves to centralize the washer with respect to the stem when the 70 spring pressure is exerted in the washer. The external diameter of the cupped portion at the bottom of the dome by the natural enlargement of the dome toward its base is calculated so as to accord with the 75 internal diameter of the coils of the spring, thereby centralizing the spring upon the washer. In case a larger spring is used 80 than is possible to make the external diameter of the cup in the natural development 85 of the dome-like boss from that portion of the top that fits over the large portion of the stem at the shoulder, then a spring seat is 90 pressed into the cupped washer such as shown in Fig. 7.

In Figs. 4, 5 and 6 a similar cupped form 95 of washer is shown in which the slot extends from the outside edge of the cupped washer to and beyond the center of the washer so that the washer may be assembled upon the stem in the manner shown by comparing Figs. 6, 5 and 4.

It will be seen that the pressure of the helical spring *b* serves to keep the washer in place in all these forms by reason of forcing the substance of the washer adjacent the restricted portion of the slot against the abrupt shoulder connecting the reduced portion of the valve stem with the portion of larger diameter.

In Figs. 4, 5 and 6 I have shown a lateral extension or tab *e* on the washer. This tab serves to indicate the direction in which the washer must be displaced laterally to disassemble it from the stem. It also serves as a 100 means for getting a hold on the washer either by the fingers or with a pair of pliers.

I have only shown this in connection with the form of washer shown in Figs. 4, 5 and 6, but it is obvious that it could be used advantageously with other forms shown.

- 5 In the above description it will be seen that this washer in a simple way embodies not only the means for maintaining its position upon the valve stem but also the means for both centralizing itself upon the valve 10 stem and centralizing the spring. It is obvious that the washer by reason of its cup-like or dome-like character of the central portion may be stamped out.

What I claim is:

- 15 1. In a spring abutment, the combination of a stem, a spring coiled thereabout, and a washer finally assembled upon the said stem by lateral movement, said washer being provided with an extension or tab by 20 which it may be disassembled from the stem by grasping the tab and pulling laterally of the stem on said tab.
2. A spring abutment, having in combination with a stem provided with a reduced 25 and shouldered portion and a spring encircling the stem, a washer constructed to form a central cup whose interior diameter is calculated to just fit over the large portion of the stem so that the washer centralizes itself 30 and whose exterior and interior gradually flare so the cup just fits in the coils of the spring to centralize the spring, the said washer being perforated at the center to fit around the reduced portion of the stem and 35 having an eccentric opening communicating with the central perforation to permit of the assembling of the washer upon the reduced portion of the stem, substantially as described.
- 40 3. A spring abutment, having in combination with a stem provided with a reduced and shouldered portion and a spring encircling the stem, a washer cupped centrally to form a boss of dome-shape, the interior

of the top of the dome-like boss being calculated to just fit over the large portion of the stem so that the washer centralizes itself and the dome-like boss enlarging toward its base so that the spring resting on the flat marginal portion of the washer is centralized by the lower portion of the boss which is enlarged to just fit into the interior of the spring, the said washer being perforated at the center to just fit around the reduced portion of the stem and having an 55 eccentric opening communicating with the central perforation to permit of the assembling of the washer upon the reduced portion of the stem, substantially as described.

4. In a device for the purpose specified, 60 the combination of a stem provided with a reduced portion forming a shoulder, a coiled spring engaging thereabout, and a washer constructed of metal of substantially uniform thickness and having a central aperture, the bordering metal for which fits around the reduced portion of the stem and lies against the said shoulder, said washer having an eccentric opening merging into the central opening by which the washer 70 can be assembled upon the stem by lateral movement to a concentric relation with respect to the stem, the said washer having its central portion cupped to provide a dome whose interior diameter near the top of the 75 dome just fits over the outside of said shoulder to centralize the washer on the stem and the dome enlarging in diameter toward its base where it merges with the outside portions of the washer to form an annular 80 flange acting as a seat for said coiled spring, the size of the base of the dome being calculated to just fit into the coiled spring to centralize the same.

In testimony whereof I sign this specification.

ERNEST E. WEMP.
